SHADING PROCESS FOR PHOTOGRAPHS

Harry J. Tuthill, St. Louis, Mo.

Application April 5, 1946, Serial No. 659,824

11 Claims. (Cl. 41—46)

1

This invention relates to processes of producing, whole or in part, drawings, pictures or other graphic compositions by means of stipple, spatter dots or areas comprising half tone or Ben Day type lines or shading.

The principal objects of the present invention are to devise a simple and economical process of quickly and easily applying such lines or shading to any fairly smooth and solid surface; to provide sharply defined dotted lines or tones of any desired contour; to vary the sizes, shape and spacing of the dots which make up the lines or shaded areas so as to produce varying tone shades or tints; and to obtain other advantages hereinafter appearing.

In the accompanying drawing, which forms part of this specification, and wherein like symbols refer to like parts wherever they occur.

Fig. 1 is a plan view of a sheet of drawing to which my stippling process is to be applied.

Fig. 2 is a similar view showing the perforated film laid upon and adhesively secured to said drawing.

Fig. 3 is a similar view, showing the white and black ink applied to the desired areas of the perforated film.

Fig. 4 is a similar view of the drawing after the perforated film has been stripped therefrom.

Fig. 5 is an enlarged fragmentary plan view of the perforated film.

Fig. 6 is an enlarged cross-sectional view on the line 6—6 in Fig. 3.

Fig. 7 is an enlarged cross-sectional view on the line 7—7 in Fig. 4; and

Figs. 8 and 9 are views similar to Figs. 3 and 4, respectively, showing a further step in my stippling process.

The invention consists in providing a thin sheet of transparent, translucent or opaque material having a multiplicity of suitably spaced perforations of the desired sizes and shape extending therethrough, laying said sheet upon any surface as that of a drawing, picture or other graphic composition, moistening said sheet with a suitable fluid which causes said sheet to closely adhere to said surface, applying fluid ink or other fluid or viscid coloring material over the said sheet so that said ink flows or is worked through the perforations therein and is deposited upon said surface in the form of dots or areas of the size and shape of said perforations, and then stripping said sheet from the drawing leaving ink dots thereon. The invention also consists in making the perforated sheet of viscose "Cellophane" (non-moistureproof cellulose film), and softening such film with water to cause it to closely adhere to the surface of the graphic composition. The invention also consists in making the perforated sheet of cellulose acetate film, and in rendering such film temporarily adhesive by applying a

2

suitable volatile solvent thereto. The invention also consists in applying to the surface, or to the graphic composition in the manner above described several dotted impositions in successive order one over another and in covering the original composition and each imposition prior to the final imposition with a protecting agent which is not disturbed by the solvent or softening agent used in rendering the perforated film adhesive. The invention also consists in the process hereinafter set forth and claimed.

The first step in my process of applying dotted lines or areas to a surface or to a drawing, painting or other graphic work or composition 1, consists in providing a thin, transparent, translucent or opaque sheet or film 2 of a thickness not more than two thousandths of an inch and of suitable softenable material with a multiplicity of small perforations 3 extending therethrough. All of the perforations 3 may be of the same size and shape and uniformly spaced, or they may vary in size and shape and spaced relation, depending on the effect desired. The perforated film 2 is laid flat over the portion of the graphic composition 1 to which the dotted line or dotted area is to be applied. A suitable softening fluid is then applied to the exposed surface of the film 2 and flows or is worked through the perforations 3 therein to the underside thereof, after which the softened film is pressed against the surface of said drawing and temporarily adheres closely thereto. Fluid or viscid ink or other liquid coloring material is then painted over the surface of the perforated film above the area that is to be treated and is worked through the perforations to such area and forms thereon a multiplicity of ink dots. The film 2 is then stripped from the drawing 1 leaving an ink dotted area of the desired shade and contour thereon. As shown in Fig. 1, the portions of the sheet of drawing 1 to which the dots are to be applied are a solid black shadow area 4 and the white area 5 enclosed within the lines defining the coat of the character indicated on said drawing, white ink 6 being applied to the perforated film to produce white dots 7 on the black area 4 and black ink 8 being applied to said film to form black dots 9 on the white area 5.

While the perforated film 2 may be made of any transparent or translucent material which may be softened with a fluid applied after the film is applied to the work 1, the materials that I have found to be most practicable are non-moistureproof "Cellophane" (cellulose film) or cellulose acetate film. The non-moistureproof "Cellophane" film is softened with water and remains soft and in close contact with the surface of the work so long as it is maintained moist or wet; and it is particularly adaptable to polished surfaces such as glass, film, or either, containing

negatives and metal plates or cuts used in photo-engraving on which the water softened film will not adversely affect a film or negative that may be thereon and will leave no residue of extraneous matter on the plate or cut which would interfere with the etching operation. In use, the "Cellophane" film is laid in the desired place on the surface to which the dotted line or area is to be applied and water applied to the film to soften it. The excess water is blotted away and the film pressed smoothly with a blotter to the surface, after which the film is covered with wet or moist blotters which are successively removed from the portion of the film to which the ink or other impositional fluid is to be applied, while continuing to cover and keep soft all of the other portions of the film so that, when all desired portions thereof have been covered with ink or other material and such material has dried, or remains viscid, the film may be removed intact, leaving on the treated surface the groups of sharply defined ink dots 7 and/or 9, corresponding in size, shape and arrangement to the perforations 3 in the "Cellophane" film.

The cellulose acetate film may be softened with a mixture of, 67 parts ethyl alcohol and 33 parts ethylene glycol mono-methyl ether. The softening agent or solvent is applied preferably with a brush to all parts of the film which, at once tends to wrinkle slightly. The wrinkles or buckles are then pressed lightly with a blotter until the film is pressed smooth, after which the film is pressed and rubbed with a piece of thin paper for about 15 seconds. The operations of applying the softener and pressing or rubbing the perforated film are repeated, after which the ink or other fluid or viscid material is applied to the desired portions of the film and passes through the perforations 3 therethrough to the surface to which the film adheres. When the imposed matter is dried or while viscid, the film is lifted or stripped intact from the surface, leaving thereon the sharply defined ink dots 7 and/or 9.

Another softening agent which I have found suitable for use with a cellulose acetate film is a mixture of 35 parts ethyl alcohol and 65 parts ethyl acetate. This mixture is more volatile and saves time (see Figs. 8 and 9) when it is desired to apply several films and impositions of quick drying ink dots 9 in consecutive order to the same surface. These mixtures are preferable because they are common softening agents whose toxicity is comparatively low and which present no great industrial hazard and do not have an objectionable odor.

In cases where it is desired to superimpose successive dotted India ink areas one over the other to a surface having an India ink drawing thereon, said surface and each successive dotted area are rubbed with a zinc stearate powder, which is insoluble in water, alcohol and ether, so that the previously applied ink will not be disturbed by the succeeding application of the film softening agent or adhere to the undersides of succeeding films.

The hereinbefore described process has many important advantages. It is applicable to any fairly smooth surface, as that of drawing paper or board, pressed fiber, wood, stone, glass, film, metal, plaster and plastics. It enables dotted lines or areas to be quickly and easily applied with relatively small cost to the desired portions of the work; and these dotted lines or areas may be made with any fluid or viscid material such

as India ink, decorative colors, engraving resist or the like. Different shading and tones may be produced with one color, by varying the size, shape and spacing of the perforations and by arranging them in geometrical or variegated patterns or by superimposition. The multiplicity of dots that make up the shaded areas all have evenly shaped, clearly defined edges and thus greatly improve the appearance of graphic compositions made with them or to which they are applied. The term "graphic composition" as used herein is intended to denote a drawing, picture, sign, decoration or any material having a substantially smooth and solid work surface; and the term "fluid ink" is intended to include any fluid or viscid material adapted for use in forming the dotted lines or areas.

Obviously, the hereinbefore described process admits of considerable modification without departing from the invention. Therefore, I do not wish to be limited to the precise process shown and described.

What I claim is:

1. The process of applying dots to a graphic 25 composition which consists in providing a thin sheet of transparent flexible material having a multiplicity of perforations extending therethrough, laying such perforated sheet upon said graphic composition, applying to the exposed face 30 of said sheet a liquid solvent therefor which flows through the perforations therein to the underside thereof and causes said sheet to removably adhere to said graphic composition, and then applying to said exposed surface of said sheet a viscous 35 marking fluid which flows through said perforations and adheres to said graphic composition in the form of dots corresponding to the shape, size and spacing of said perforations.

2. The process of applying dots to a surface 40 which consists in providing a thin sheet of transparent flexible material having a multiplicity of perforations extending therethrough, laying such perforated sheet upon said surface, applying to the exposed face of said sheet a liquid solvent 45 therefor which flows through the perforations therein to the underside thereof and causes said sheet to removably adhere to said surface and provides a fluid tight seal between said surface and said sheet around the perforations therein, and then applying to said sheet a viscous marking fluid 50 which flows through said perforations and adheres to said surface in the form of dots corresponding to the shape, size and spacing of said perforations.

3. The process of applying dots to a graphic 55 composition which consists in providing a thin sheet of transparent flexible material having a multiplicity of perforations extending therethrough in a predetermined manner, laying such 60 perforated sheet upon said graphic composition, applying to the exposed face of said sheet a liquid solvent therefor which flows through the perforations therein to the underside thereof and causes said sheet to adhere temporarily to said graphic 65 composition, applying to said exposed surface of said sheet a fluid ink which flows through said perforations and is deposited on said graphic composition in the form of dots corresponding to the shape, size and spacing of said perforations, and 70 then stripping said sheet from said graphic composition, leaving the ink dots thereon.

4. The process of applying dots to a graphic 75 composition which consists in providing a thin sheet of transparent flexible soluble material having a multiplicity of perforations extending there-

through, laying such perforated sheet upon said graphic composition, applying to the exposed face of said sheet a liquid solvent therefor which flows through the perforations therein to the underside thereof and causes said sheet to removably adhere to said graphic composition, applying to said exposed surface of said sheet a fluid ink which flows through said perforations and is deposited on said graphic composition in the form of dots corresponding to the shape, size and spacing of said perforations, and then stripping said sheet from said graphic composition, leaving the ink dots thereon.

5. The process of applying dots to a graphic composition which consists in providing a transparent cellulose flexible film having a multiplicity of perforations extending therethrough, laying such perforated film upon said graphic composition, applying to the exposed face of said sheet a liquid solvent therefor which flows through the perforations therein to the underside thereof and causes said film to removably adhere to said graphic composition, applying to said exposed surface of said film a fluid ink which flows through said perforations and is deposited on said graphic composition in the form of dots corresponding to the shape, size and spacing of said perforations, and then stripping said film from said graphic composition, leaving the ink dots thereon.

6. The process of applying dots to a graphic composition which consists in providing a transparent water soluble cellulose film having a multiplicity of perforations extending therethrough, laying such perforated film upon said graphic composition, applying to the exposed face of said sheet water which flows through the perforations therein to the underside thereof and softens the same, and renders the underside adhesive, pressing the softened film against said graphic composition to cause it to removably adhere flatwise thereto, applying to said exposed surface of said film a fluid ink which flows through said perforations and is deposited on said graphic composition in the form of dots corresponding to the shape, size and spacing of said perforations, and then stripping said film from said graphic composition, leaving the ink dots thereon.

7. The process of applying dots to a graphic composition which consists in providing a transparent cellulose film having a multiplicity of perforations extending therethrough, laying such perforated film upon said graphic composition, applying to the exposed face of said film a liquid solvent therefor which flows through the perforations therein and renders the underside thereof adhesive, pressing said film against said graphic composition to cause it to removably adhere thereto, applying to said exposed surface of said film a fluid ink and working said ink through said perforations so that it is deposited on said graphic composition in the form of dots corresponding to the shape, size and spacing of said perforations, and then stripping said film from said graphic composition, leaving the ink dots thereon.

8. The process of applying dots to a pen and ink drawing which consists in providing a transparent cellulose acetate film having a multiplicity of perforations extending therethrough, laying such perforated film upon said drawing, applying to the exposed face of said film a volatile liquid solvent therefor which flows through the perforations therein and renders the underside thereof adhesive, pressing said adhesive film

against said drawing to cause it to removably adhere flatwise thereto, and applying to said exposed surface of said film a fluid ink which flows through said perforations and is deposited on said drawing in the form of dots corresponding to the shape, size and spacing of said perforations.

9. The process set forth in claim 8 wherein the steps of applying the solvent to the film and pressing the film against the graphic composition are repeated before the fluid ink is applied to the film.

10. The process of applying dots to a graphic composition which consists in providing a thin sheet of transparent flexible material having a multiplicity of perforations extending therethrough, laying such perforated sheet upon said graphic composition, applying to the exposed face of said sheet a liquid solvent therefor which flows through the perforations therein to the underside thereof and causes said sheet to removably adhere to said graphic composition, applying to said exposed surface of said sheet a fluid ink which flows through said perforations and is deposited on said graphic composition in the form of dots corresponding to the shape, size and spacing of said perforations, stripping said sheet from said graphic composition, covering the dotted area with an agent which is resistant to the liquid solvent for said sheet, laying a second sheet of perforated transparent material over the dotted area treated with such resistant agent, and then applying the liquid solvent and the ink to said second sheet in the same manner in which they are applied to the first sheet.

11. The process of applying dots to a graphic composition which consists in providing a thin sheet of transparent cellulose film having a multiplicity of perforations extending therethrough, laying such perforated film upon said graphic composition, applying to the exposed face of said sheet a volatile liquid solvent therefor which flows through the perforations therein to the underside thereof and causes said film to removably adhere to said graphic composition, applying to said exposed surface of said film a fluid ink which flows through said perforations and is deposited on said graphic composition in the form of dots corresponding to the shape, size and spacing of said perforations, removing said film, rubbing the dotted ink area with a zinc stearate powder which is resistant to said solvent, laying a second perforated transparent cellulose film over the dotted area which has been treated with the resistant powder, and then applying the liquid solvent and the ink to said second sheet in the same manner in which they are applied to the first sheet.
